CHENILLE YARNS AND THEIR MANUFACTURE

Walter A. Rice, Amsterdam, N. Y., assignor, by mesne assignments, to Mohasco Industries, Inc., Amsterdam, N. Y., a corporation of New York

Application November 6, 1953, Serial No. 390,593

8 Claims. (Cl. 28—72)

This invention relates to chenille yarns and their production and is concerned more particularly with a novel chenille yarn useful for all the usual purposes, for which conventional chenille yarns or strips of chenille fur are employed, and capable of being produced more rapidly and at less cost. In addition, the invention comprehends a method for the manufacture of the new yarn. The yarn of the invention may be advantageously employed to provide the pile of chenille carpeting and a form of the yarn suitable for such use will, accordingly, be illustrated and described in detail for purposes of explanation.

The chenille fur now used in the production of chenille carpets is made by weaving on an ordinary loom a fabric, commonly referred to as a chenille blanket, in which the warp yarns are relatively small and are drawn through the reed to provide small groups of warp ends spaced apart a distance about equal to twice the height of the pile desired and frequently including leno ends. The filling in the blanket is a heavy yarn suitable for pile elements and ordinarily of wool or of a wool blend. After completion of the fabric, it is cut lengthwise along lines lying midway between the groups of warp ends and is thus converted into a plurality of strips of chenille fur. The strips are prepared for use in carpet weaving in various ways, as, for example, by folding or pressing the lengths of filling yarn extending from opposite sides of the warp ends interlaced therewith, so that the strips are of V-section. While such strips of chenille fur are satisfactory for use in chenille fabric floor coverings, it will be apparent that the production of the strips by weaving and cutting a chenille blanket is slow and expensive and the cost is increased by the finishing operations necessary.

The present invention is directed to the provision of a novel chenille yarn, which is satisfactory for use in carpet manufacture in place of strips of chenille fur and can be produced at high speed on a sewing machine of the type employed in tufting operations. The new yarn comprises a relatively bulky base yarn, which is provided with a plurality of pile elements projecting laterally from the base yarn at points spaced along it. The pile elements are made of a yarn suitable for the pile in the fabric to be produced and ordinarily of wool or a wool blend. The pile yarn is ordinarily of somewhat lighter weight than the base yarn and the pile elements are held in place by end sections, which extend through the base yarn in pairs with the end sections of each pair continuous with end sections of other elements lying, respectively, on opposite sides of the pair.

In the production of the new chenille yarn, the base yarn is advanced beneath a needle, which passes a loop of pile yarn through the base yarn at spaced points, while the base yarn is under tension. As each loop is exposed beyond the base yarn, it is held by a looper, while the needle is retracted, and the loop so formed may be released uncut by the looper or may be severed by a suitable knife. The operations described are repeated, so that the

2

loops are passed through the base yarn at short intervals along the length of the latter.

For a better understanding of the invention, reference may be made to the accompanying drawings, in which

5 Fig. 1 is a view in longitudinal section of a machine for producing the new yarn;

Figs. 2 and 3 are sectional views on the lines 2—2 and 3—3 of Fig. 1;

10 Fig. 4 is a view similar to Fig. 3 showing a length of pile yarn, carried by a needle, prior to insertion into the base yarn; and

Figs. 5 and 6 are views in side elevation, with parts broken away, of lengths of two different forms of the new

15 yarn. The yarn of the invention comprises a base yarn 10, which is preferably relatively large and bulky and is made of a plurality of singles components plied together with a relatively low ply twist. The components of the base yarn may be spun from stock of any suitable fiber, such as wool, wool blends, jute, cotton, etc., and the yarn does not require dyeing.

The base yarn carries a plurality of pile elements made of a pile yarn 11, which is of smaller size than the base

25 yarn and is preferably made of a plurality of singles components plied together. The components of the pile yarn

may be spun from any fibrous stock commonly employed in pile yarns, such as wool, wool blends containing synthetic fibers, etc. The pile elements project laterally from

30 the base yarn at the points spaced along the latter in a row and may be pile loops 12 or pile tufts 13 produced by cutting pile loops. The pile elements have end sections

35 14, which extend through the base yarn and lie in contact within the latter. Each end section 14 is connected to the adjacent end section along the base yarn by a length

15 of the pile yarn, which lies snugly against the surface of the base yarn.

The new yarn may be made most conveniently on a sewing

40 machine of the type used for tufting purposes and having a plurality of needles. In such a machine, a plu-

rality of ends of base yarn 10 are drawn from respective supply rolls 16 and pass side by side over the bed plate

17 of the machine and through a suitable tension device

18. The device may include a bottom plate 19a resting

on the bed plate and a top plate 19b pressed toward the

bottom plate by a plurality of springs 20 encircling posts

21 threaded into the bed plate and extending through

openings in the plates 19a, 19b. Each spring bears at one

50 end on plate 19b and at the other against a washer 22

beneath a nut 23 on the threaded upper end of the post.

From the tension device, each base yarn passes through

25 an individual guide 24 mounted on top of the throat plate

26, over which the respective yarns travel on their way

55 to a pair of rolls 27, 28, which grip and advance the yarns.

The slots 26 in the throat plate have downwardly con-

vergent walls, as shown, and, in their travel over the slots,

the yarns pass beneath a presser foot 29.

Between its guide and the presser foot, each yarn passes

60 beneath a needle 30, which lies above a slot 26 in the

throat plate. The needles are carried by a needle bar

reciprocated vertically in the operation of the machine

and each needle is supplied with pile yarn 11 from a sup-

ply package 31. A looper 32 is mounted beneath each

65 slot 26 to cooperate with a needle 30. The loopers 32 are

of conventional construction and they are mounted on a

rock shaft 33 actuated by means acting on crank arm 34.

Each looper has a hook 32a at its upper end for insertion

70 between its needle and the loop of pile yarn carried by

the needle through the base yarn. The machine shown

is also provided with a knife 35 for cutting the successive

loops engaged and held by each looper and the knives are

mounted on respective arms 36 attached to a shaft 37, which is rocked at the appropriate time by an arm 38 to cause the knives to cooperate with the loopers to sever the loops thereon.

The finished yarn issuing from between rolls 27, 28 is passed around a guide roll 39 and is then wound into a package 40 on a mandrel 41. The mandrel rests upon a driven roll 42 and its ends are guided between vertical guides 43.

In the operation of the sewing machine, a plurality of base yarns are simultaneously drawn from their respective supply packages by the rolls 27, 28 and the yarns are individually maintained under tension by the tension device 18. Upon each downward movement of the needle bar, the needles 30 pass loops 12 of the pile yarn through the base yarns and, as a base yarn is penetrated by its needle, it moves downward slightly and is sustained by the side walls of its slot 26 in the throat plate. While the needle is projecting through the base yarn, its looper enters the loop of pile yarn, which has been inserted by the needle, and, as the needle is retracted, the looper holds the loop. As the needle rises, the base yarn is prevented from rising with it by the presser foot. After the base yarn has advanced the desired distance, the needle again passes a loop through the base yarn, and the length of pile yarn, which lies against the upper surface of the base yarn and connects the new loop to the old one, is drawn taut, since the old loop is retained by the looper until the new loop has been inserted. Upon insertion of the new loop, the old loop is severed or released by the loop, depending upon whether the yarn produced is to have pile elements in the form of pile tufts or pile loops.

It will be apparent that the new chenille yarn can be produced rapidly and at low cost by the operations described. Multi-needle sewing machines having a large number of needles are commercially available and require little modification to carry on the production of the new yarn. Such sewing machines are capable of adjustment, so that the length of the pile elements can be varied as desired and the machines can make many more stitches per minute than the number of picks of filling, which can be inserted by a loom weaving a chenille blanket. Also, such a sewing machine may have many more needles than the number of strips of fur, which can be obtained from a chenille blanket made on a loom ordinarily used for weaving such a fabric. The new yarn can thus be produced more rapidly than strips of chenille fur and it can be used at once and without preliminary finishing operations.

Another advantage of the new yarn is that it can be used in the manufacture of chenille carpeting to produce a pile, in which the pile elements are loops. Because of the manner in which it is made, chenille fur produces a pile fabric having a cut pile surface. The use of the new yarn thus makes it possible to provide chenille carpeting with a surface appearance not obtainable heretofore.

I claim:

1. A chenille yarn, which comprises a base yarn and lengths of pile yarn mounted on the base yarn in a row lengthwise of the latter, each length of pile yarn having an intermediate portion lying against the side of the base yarn and end sections extending through the base yarn and projecting beyond the opposite side thereof to provide tuft legs.

2. A chenille yarn, which comprises a base yarn and

lengths of pile yarn mounted on the base yarn in a row lengthwise of the latter, each length of pile yarn having an intermediate portion lying against the side of the base yarn and end sections extending through the base 5 yarn and projecting beyond the opposite side thereof to provide tuft legs, the adjacent end sections of successive lengths of pile yarn extending through the base yarn in contact with each other.

3. A chenille yarn, which comprises a base yarn plied of a plurality of singles strands and lengths of pile yarn mounted on the base yarn in a row lengthwise of the latter, each length of pile yarn having an intermediate portion lying against the side of the base yarn and end sections extending through the base 10 yarn and projecting beyond the opposite side thereof to provide tuft legs.

4. A chenille yarn, which comprises a relatively heavy base yarn and lengths of a pile yarn of lighter weight mounted on the base yarn in a low lengthwise of the latter, each length of pile yarn having an intermediate portion 15 lying against the side of the base yarn and end sections extending through the base yarn and projecting beyond the opposite side thereof to provide tuft legs.

5. A chenille yarn, which comprises a base yarn and pile elements of yarn projecting laterally from the base 20 yarn at points spaced along the base yarn, the pile elements being held in place by end sections extending through the base yarn with a pair of end sections lying in contact within the base yarn at each point, the end sections of each such pair being continuous with end sections lying, respectively, on opposite sides of said pair.

6. A method of making a chenille yarn, which comprises drawing a base yarn from a source of supply, passing loops of a continuous pile yarn through the base 25 yarn at relatively short intervals and drawing the pile 30 yarn snugly against the base yarn between adjacent loops, and severing the loops.

7. A method of making a chenille yarn, which comprises drawing a base yarn from a source of supply while maintaining the yarn under tension, passing loops of a 35 continuous pile yarn through the base yarn at relatively short intervals, while supporting the base yarn at opposite sides, and drawing the pile yarn snugly against the base 40 yarn in front of each loop, as the latter is inserted.

8. A method of making a chenille yarn, which comprises drawing a base yarn from a source of supply while maintaining the yarn under tension, passing a first loop 45 of a continuous pile yarn through the base yarn, while supporting the base yarn at opposite sides, passing a second loop of said pile yarn through the base yarn, while holding said first loop, whereby the section of said pile 50 yarn between said loops is drawn snugly against the base yarn.
